UNITED STATES PATENT OFFICE.

JOSEPH C. TIFFANY, OF PORTSMOUTH, NEW HAMPSHIRE.

IMPROVEMENT IN GASOMETERS OR GAS-HOLDERS.

Specification forming part of Letters Patent No. 135,172, dated January 21, 1873.

To all whom it may concern:

Be it known that I, JOSEPH CAPRON TIFFANY, of Portsmouth, in the county of Rockingham and State of New Hampshire, have invented certain new and useful Improvements in Gasometer, of which the following is a specification:

My invention has for its object to produce a gasometer which is composed essentially of a stationary bottom plate and a movable head or crown, to which are attached flexible curtains of India rubber, cloth, or other fabric rendered impervious to gas and air. The invention consists in attaching the fabric constituting the curtain or body of the gasometer to the bottom plate and movable crown or head by means of annular bands, links, or rods, which compress or clamp the fabric between the edges of the plates and said bands for forming an air and gas tight joint. The invention also consists in applying to the flexible curtains or body of the gasometer a series of loops or eyes traveling on stationary guide-rods on the receiving-frame for maintaining a true shape of the gasometer when expanded by the gas, and for preventing uniform crimping of the same when in a collapsed state. The invention also consists in making the bottom of the gasometer with a concave or corrugated upper surface forming a receptacle for collecting tar or any condensable matter that may pass the purifiers or condensers. The invention also consists in applying to said concave bottom a series of rods or a wire-gauze or perforated diaphragms for preventing the curtain or body of the gasometer when in a collapsed state from coming in contact with the condensed matter collected in the concave bottom. The invention also consists in the employment of one or more siphon-tubes applied to a concave or corrugated bottom for the escape of the condensed material, and for preventing the entrance of the external atmosphere into the gasometer. The invention also consists in constructing the movable crown or head of the gasometer partially of a skeleton-frame or metallic rims and a flexible covering attached by the same clamping-bands or fastening devices, which secure the flexible body or curtain in position. The invention also consists in attaching to the interior or exterior of the curtain or body of the gasometer a series of strengthening-hoops for preventing an inward

or outward collapsing of the curtain so as to retain the form of the gasometer.

In the drawing, Figure 1 is a vertical central section of the gasometer, its receiving-frame, false bottom, convex bottom, and a siphon or trap. Figs. 2 are detached sectional views of the solid and skeleton movable crown or head illustrating the manner of securing the flexible curtain to the same. Fig. 3 is a modification representing the movable head composed of a skeleton-frame with its flexible fabric.

The frame for receiving and sustaining the gasometer is partially composed of the base rims A B, forming, in connection with the arms C, a skeleton-cradle for the reception of the bottom D of the gasometer or receiver. A series of vertical standards, E, with upper and lower bifurcated ends for the reception of the short projecting arms F on the peripheries of the lower rim A and upper rim G comprises the frame proper, within which the gasometer is arranged to rise and fall by its expansion when filling and contraction when delivering. The upper rim G is combined with the central rim H and radiating arms I to form a skeleton top, as shown. The bottom D of the gasometer is made of a concave or corrugated form in its upper surface, and may in some instances be correspondingly formed on its under surface to fit into the cradle or stationary base A B C. The curtain or body K of the gasometer is constructed of India-rubber cloth, paper, or other suitable material rendered impervious to gas, liquid, or air, and the lower and upper edges of the same are respectively secured to the bottom D and movable solid or skeleton crown or head L by means of clamping bands or rings M, (made in one or more parts,) which firmly clamp or compress the fabric to form a tight joint. The peripheries of the bottom and movable crown may be corrugated or serrated, or grooved seats may be provided for receiving the edges of the fabric, and the clamping rings or bands may be correspondingly shaped and formed to compress the fabric into said seats or corrugated surfaces to produce an air-tight joint. The clamping bands or links are preferably separated or divided, and are provided with ears or flanges N for the passage of tightening-bolts O or other suitable devices. The body of the gasometer is generally of a cylindrical shape; but when desired to suit special

locations or compartments in which the same is to be placed it is made either of an oval, triangular, square, or polygonal shape. In such instances it is obvious that the concave bottom, crown or movable head, and clamping-bands are correspondingly shaped. For strengthening the flexible curtain of the gasometer, and for imparting the necessary rigidity to the same when in a distended state and filled with gas, I apply to the interior or exterior surface of the same a series of hoops or bands, V, which may be of a rectangular, cylindrical, oval, or T-shaped form, as found most expedient for the purpose. The arrangement of the hoops within the flexible curtain also prevents the same from falling inward or outward; and, further, they preserve the form of the gasometer as the same is being expanded by the inflow of gas, and prevent a regular uniform crimping when contracted by the discharge of the same. The strengthening-hoops are maintained in position by means of loops or bands which are formed with the curtain or body of the gasometer in the process of manufacture; or they may be separately attached thereto in any preferred manner. The supporting-frame has attached to inner portion in proper relation to the gasometer a series of vertical rods or stems, P, adapted for the reception of loops or eyes Q, secured to the fabric of the gasometer in any suitable manner, but preferably by a surrounding band of vulcanized rubber, which may itself be formed with the loops or eyes. To the rim or elevated portion of the bottom D is attached a diaphragm or false bottom, R, of wire-gauze. Perforated metal or parallel rods may be resorted to for accomplishing the same result. Between said diaphragm or plate and the concave or corrugated bottom D is formed a receptacle or chamber for the reception of tar or other condensable material, which, by its gravity, settles to the bottom of the gasometer, and enters the receptacle through the perforated plate, wire-gauze, or rods. One or more discharge- orifices are made in the bottom D, as shown in the several figures, to communicate with one or more siphon-tubes, S, to serve to convey the tar or condensed material into a suitable receptacle, and said tube or tubes being always filled, a liquid seal is formed for preventing the admission of the external atmosphere into the gasometer.

Instead of forming the top or head of the gasometer of a solid or rigid plate of metal, it may be made of a skeleton shape, as shown in Fig. 3, and have attached to it a flexible covering, T, applied to its under or upper side, and clamped between the bands and edge of the head.

This construction of head, while being perfectly gas and air tight, possesses the advantage of being non-corrosive, and of imparting a uniform pressure upon the gas when descending.

From the above description it will be seen

that the gas, upon its entrance into the gasometer, distends or expands the same, producing a perfectly plane and true form of the desired shape, and when discharged through the pipe U, extending to the burners, the descent of the gasometer will be uniform, without any tendency to an inward or outward displacement, the guide-loops moving on the vertical stems, or the inside hoops or bands preventing such a result. The lower diaphragm or rods will prevent the flexible curtain when collapsed from coming in contact with the condensed substance or material collected in the concave bottom, which would necessarily be caused to adhere to the fabric, if no such provision were made.

A suitable counterbalance mechanism is connected with the gasometer-body at the proper time for assisting the pressure of gas in returning the same to its distended or expanded state, and thus preventing too great a pressure upon the flexible body.

I do not desire to restrict myself to the form of receiving-frame represented in the drawing, as the same may be made solid, or with closed sides, or a simple series of rods may constitute the sides of the frame.

I claim as my invention—

1. The stationary bottom D and movable crown or head L of a gasometer, connected together by a flexible curtain or body, K, said curtain being guided in its vertical movement by loops or eyes Q, traveling on guide-stems P, substantially as and for the purpose set forth.

2. The flexible body K of the gasometer, secured to the bottom D and movable head L by clamping bands or rings M, substantially as shown and described.

3. The bottom D of a gasometer made concave or corrugated for the reception of condensed material or substance, as described.

4. A screen or false bottom, arranged and supported at or near the bottom of a gasometer, substantially as described.

5. The combination, with a concave or corrugated bottom, D, of the diaphragm or false bottom R, substantially as and for the purpose specified.

6. One or more siphon or discharge tubes, S, combined with the bottom D of a gasometer, for the purpose specified.

7. The movable crown or top L of the gasometer, consisting of a skeleton metallic head and a flexible covering attached to the same, substantially as and for the purpose described.

8. One or more hoops or bands connected with the flexible curtain of a gasometer, for the purpose specified.

In testimony that I claim the foregoing I have hereunto set my hand this 15th day of January, 1873.

JOSEPH C. TIFFANY.
